David L. Spero,

Milans & Milans. Attorneys:

UNITED STATES PATENT OFFICE.

DAVID LAWRENCE SPERO, OF BROWNSVILLE, TEXAS.

DEMOUNTABLE-RIM-FASTENING MEANS.

1,347,128.

Specification of Letters Patent. Patented July 20, 1920.

Application filed October 22, 1919. Serial No. 332,442.

To all whom it may concern:

Be it known that I, DAVID LAWRENCE SPERO, a citizen of the United States, residing at Brownsville, in the county of Cameron and State of Texas, have invented certain new and useful Improvements in Demountable-Rim-Fastening Means, of which the following is a specification, reference being had therein to the accompanying drawing.

This invention relates to improved fastening means for demountable rims.

The object of the invention is to provide improved fastening means adapted to securely hold the demountable rim on the wheel and capable of being easily and quickly operated to fasten the rim in place and release the same.

Another object of the invention is to provide improved quickly operable rim-fastening means adapted to be disposed compactly about the wheel structure when in rim-fastening position, substantially free from projecting parts and the liability of accidental release.

A further object is to provide an improved simple inexpensive form of rim fastening means of the character referred to, adapted to be readily employed with the standard types of wheels.

The invention, with other objects and advantages thereof, and the particular construction, combination and arrangement of parts comprising the same, will be understood from the following detailed description, when considered in connection with the accompanying drawings forming part hereof and illustrating embodiments of the invention.

In the drawings:—

Figure 1 is a transverse section of a part of one of the standard types of wheels equipped with rim fastening means constructed in accordance with the present invention, the rim fastening means being shown in rim-holding position in full lines, and the position of the parts of the fastening means when the clamping lever has been swung to release position being indicated in dotted lines.

Fig. 2 is an end elevation taken from the left-hand side of Fig. 1.

Fig. 3 is an end elevation from the right-hand side of Fig. 1.

Fig. 4 is a detail view of a portion of the inner face of the wheel felly.

Figs. 5 and 6 are detailed views of modified forms of rim-engaging members.

While in the drawings, I have illustrated by way of example specific embodiments of the invention for two of the standard types of wheels, it will, of course be understood that variations and changes in the particular construction of fastening means shown, and the carrying out of the invention in other forms with different types of wheels as will appeal to those skilled in the art and falling within the scope of the appended claims, may be practised without departing from the spirit of the invention.

In the drawings, 1 designates the felly of the wheel provided with a fixed rim 2 having a flange 3, and 4 is the demountable rim.

The particular construction of my improved fastening means illustrated in the drawings, comprises a bolt 5 adapted to extend through a transverse opening 6 in the felly 1, with end portions 5^a—5^b projecting from opposite sides of the felly. On one end portion 5^a of the bolt 5 is a rim-engaging member 7 adapted to be moved laterally into and out of holding engagement with the demountable rim 4, and to be completely removed or turned down to permit the demountable rim to be placed on and removed from the wheel. In the present instance, the rim-engaging member 7 is shown formed integral with the bolt 5, the latter being adapted to slide and rotate in the opening 6 in the felly, to provide for the necessary adjustments of the rim-engaging member. The rim-engaging member (Figs. 1 and 2) consists of a wedge-shaped part extending inwardly from the outer end of a block or plate 8 integral with the end portion 5^a of the bolt 5, said plate or block 8 at its lower part having a hook extension 9.

10 and 11 designate connections with opposite end portions 5^a—5^b of the bolt 5, and 12 is a lever pivotally connected with said connections, said parts constituting a clamp adapted to force and maintain the rim-engaging member 7 in rim-engaging position to securely hold the demountable rim on the wheel. The connection 10 is shown as consisting of a metal strap or plate provided with an apertured part 10' at one end to engage the end portion 5^b of the bolt and having angularly related portions 10^a—10^b and 110 curved as shown, to extend inwardly of the wheel to the inner side of the felly, the lever

12 being pivotally connected to the inner end of said strap. The connection 11 takes the form of a metal loop or bail having angularly related portions 11^a—11^b, one end 5 of the bail being pivotally connected at 13 with the lever 12, the other end of the bail being adapted to detachably engage the hook extension 9 on the end portion 5^a of the bolt 5.

10 In Fig. 2 of the drawings, the clamp is shown in open or unlocked position. From this position the lever 12, which is curved or bent as shown, is adapted to be swung laterally and down against the strap 10 to 15 the position indicated in Fig. 1 of the drawings, the rim-engaging member being moved laterally into tight-holding engagement with the rim, the loop or bail 11, strap 10, and lever 12 assuming a compact relation 20 about the wheel. To dismount the rim 4, the lever 12 is swung back to open or unlocked position, the loop 11 and connection 10 disengaged from the hook extension 9 and end portion 5^b of the bolt, and the bolt 25 5 and rim-fastening member 4 completely removed, or the bolt 5 may be shifted laterally only a slight distance and then partially rotated to remove the rim-engaging member from over the felly and to turn the 30 same out of the way.

As shown in Fig. 4, wear plates *a* may be provided at the inner side of the felly at points about the same as the location of the rim fastening means.

35 As will be appreciated, the construction hereinbefore described affords a very firm and secure fastening means for the demountable rim, outward pressure laterally against the rim-engaging member 7 acting 40 to more tightly bind the parts together. As an additional safeguard against the accidental release of the lever, separate locking means are provided for the lever. This locking means is shown in the drawings as 45 a substantially U-shaped clip member 14 having end portions 14^a—14^b to engage over the outer end of the lever 12 and the adjacent end portion 5^b of the bolt 5, and serving to lock the lever to the bolt. The clip 50 member 14 is adapted to be passed through an aperture 15 in the end of the lever 12 and then turned to bring the portions 14^a—14^b over the end of the lever and bolt. The portion 14^b of the clip, which is shaped as 55 shown to afford a finger grip or handle, is adapted to be sprung over the portion 16 of the lever into the space between said portion 16 and the opposite raised portion 17 of the lever.

60 Any desired number of the fastening devices may be employed about the wheel. Instead of the wedge-shaped construction of rim-engaging member shown in Figs. 1 and 2, other forms of rim engaging members 65 may be employed as occasion may require,

as for instance that shown in Fig. 5 of the drawing, and the rim-engaging members may be in the form of relatively long segments 18 as illustrated in Fig. 4 of the drawing.

70

What I claim is:

1. A device of the class described including a bolt adapted to engage and extend transversely of the felly of the wheel with portions projecting from opposite sides of the felly, a rim-engaging member on one end portion of the bolt, a lever, connections leading from opposite end portions of the bolt, the lever being pivotally connected with said connections and adapted to be 80 swung in one direction to clamp the rim-engaging part in rim-holding position.

2. A device of the class described including a bolt adapted to engage and extend transversely of the felly of the wheel with 85 portions projecting from opposite sides of the felly, a rim-engaging member on one end portion of the bolt, a lever, connections leading from opposite end portions of the bolt, one of said connections being detachable, the lever being pivotally connected with said connections and adapted to be 90 swung in one direction to clamp the rim-engaging part in rim-holding position.

90

3. A device of the class described including a bolt to engage and extend transversely of the felly of the wheel with portions projecting from opposite sides of the felly, a rim-engaging member and a hook part on one end portion of the bolt, a part extending inwardly of the wheel from one end portion of the bolt, a lever pivotally connected to said part, and a link member pivotally connected with the lever and adapted to detachably engage said hook part.

95

4. A device of the class described including a bolt adapted to engage and extend transversely of the felly of the wheel with portions projecting from opposite sides of the felly, a rim-engaging member on one end portion of the bolt, a part connected with one end portion of the bolt and extending to the inner side of the felly, a lever pivotally connected with said part at the inner side of the felly, and a pivotal link connection between the lever and the other end portion of the bolt, said lever being adapted to be swung to a position adjacent the felly and to clamp the rim-engaging member in rim-engaging position.

100

5. A device of the class described including a bolt adapted to engage and extend transversely of the felly of the wheel with portions projecting from opposite sides of the felly, a rim-engaging member on one end portion of the bolt, a curved strap adapted at one end to slidably engage one end portion of the bolt and to extend to the inner side of the felly, a lever pivotally connected with the inner side of the strap, and 125

115

120

130

a pivotal link connection between the lever and the other end portion of the bolt, said lever being adapted to be swung laterally and down against the strap to clamp the 5 rim-engaging member in rim-engaging position.

6. A device of the class described including a bolt adapted to engage and extend transversely of the felly of the wheel with 10 portions projecting from opposite sides of the felly, a rim-engaging member on one end portion of the bolt, a part having angularly related portions and provided at one end with an apertured part to slidably engage 15 one end portion of the bolt, said part being adapted to extend to the inner side of the felly, a lever pivotally connected with the inner end portion of said part, and a pivotal detachable link connection between 20 the lever and the other end portion of the bolt, said lever being adapted to be swung laterally and down to a position against the felly and to clamp the rim-engaging member in rim-engaging position.

25 7. A device of the class described including a bolt adapted to engage and extend transversely of the felly of the wheel with portions projecting from opposite sides of the felly, a rim-engaging member on one 30 end portion of the bolt, a part connected with one end portion of the bolt and extending to the inner side of the felly, a lever pivotally connected with said part at the inner side of the felly, a pivotal link connection between the lever and other end 35 portion of the bolt, the lever being adapted to be swung laterally to a position adjacent the wheel and to clamp the rim-engaging member in rim-engaging position, one end of the lever when in locking position extending adjacent one end portion of the bolt, and locking means for the lever comprising a substantially U-shaped latch member adapted to engage an apertured part on the lever, with its end portions fitting over the 40 bolt and lever.

to be swung laterally to a position adjacent the wheel and to clamp the rim-engaging member in rim-engaging position, one end of the lever when in locking position extending adjacent one end portion of the bolt, and locking means for the lever adapted to engage over the bolt and the outer end of the lever when in locking position.

8. A device of the class described including a bolt adapted to engage and extend transversely of the felly of the wheel with portions projecting from opposite sides of the felly, a rim-engaging member on one end portion of the bolt, a part connected 45 with one end portion of the bolt and extending to the inner side of the felly, a lever pivotally connected with said part at the inner side of the felly, a pivotal link connection between the lever and other end 50 portion of the bolt, the lever being adapted to be swung laterally to a position adjacent the wheel and to clamp the rim-engaging member in rim-engaging position, one end of the lever when in locking position extending adjacent one end portion of the bolt, and locking means for the lever comprising a substantially U-shaped latch member adapted to engage an apertured part on the lever, with its end portions fitting over the 55 bolt and lever.

In testimony whereof I hereunto affix my signature in the presence of two witnesses.
